Filed Aug. 10, 1970, Ser. No. 24,406

Term of patent 14 years

Int. Cl. D12—14

U.S. Cl. D14—3

FIG. 1 is a perspective view of a golf bag cart embodying my new design and looking at the cart from a position forward thereof and slightly offset towards the left;

FIG. 2 is a perspective view of the same golf bag cart looking at the same from a forward position but considerably offset towards the left;

FIG. 3 is a perspective view of the same cart showing the opposite side of the cart from that shown in FIG. 2;

FIG. 4 is a perspective view looking from above at the rear of the same cart and showing especially the details of the upper part of the housing; and

FIG. 5 is a cross sectional view, on a reduced scale, taken along section line 5—5 of FIG. 4 showing the cross sectional shape of the housing in the area of the bottom of the bag-receiving depression.

I claim:

The ornamental design for a golf bag cart, as shown.
